POPCORN BOX WITH POURING SPOUT

Sharrell E. Smith, Ashland, Ohio

Application May 26, 1947, Serial No. 750,395

1 Claim. (Cl. 229—39)

1

The object of my invention is to provide a cardboard box having novel end flaps for fastening the bottom end of the box together and other and different novel flaps at the top of the box for fastening the major portion of the top of the box together while providing other flaps which form a pouring spout which can be opened to empty out the pop corn in the box.

I attain the objects of my invention by the box illustrated in the accompanying drawings in which—

Figure 1 is a perspective view of an embodiment of the invention with the spout open;

Fig. 2 is a top plan view of the top of the box in closed position;

Fig. 3 is a plan view of the complete blank from which the box is made; and

Fig. 4 is a bottom plan view of the bottom of the box in closed position.

Like characters of reference indicate like parts in each of the several views.

The box 1 has end flaps 2 having a diagonally edged portion 3 and an approximately square tongue 4. The box 1 has a bottom side flap 5 with tapered or diagonal edges 6, and a broad tongue 7. An opposite side flap 8 has relatively narrow nearly square extensions 9. To form the bottom of the box, the flap 8 is first folded in and the end flaps 2 are folded over the side flap 8. The flap 7 is then folded over the flaps 2 and pushed inward until flap 7 is engaged under flap 8, thus locking the flaps of the bottom of the box together.

At the top of the box an end flap 10 has a diagonal edge 11 and a tongue 12. A side flap 13 has a diagonal edge 14 and a slight projection 15, extending in the same general direction as the diagonal edge. The opposite edge 16 has a slight projection 17. The body of the box is fastened by a narrow sealing flap 23. Flap 18 is provided with a tongue 19 to underlie flap 10 and a slight projection 24 at the other end extending beyond edge 16' overlies tongue 21.

To close top, flap 18 is just folded in and the end flap 10 is folded down on top of flap 18. Then flap 13 is folded over and the complete top of box is spread open to allow flap 13 to be inserted under flap 18. On opposite end the flaps 22 are folded in and flap 21 is folded across them and inserted under flaps 18 and 13, and engaged by their extensions 24.

When it is desired to pour out pop corn from

the box, the pouring spout element 21 is pulled out and flaps 22 raised, leaving the other flaps on the top of the box closed, so that a limited amount of pop corn can be poured out through the pouring spout. Flaps 13 and 18 have slight extensions 24 to engage element 21. Slits 25 facilitate opening flap 21.

The box is especially adapted for holding pop corn but it may also be used for holding any light material and may be readily opened to pour out the contents.

What I claim is:

A carton comprising opposed side walls and opposed end walls, interengaging flaps formed on the bottom edge of said side and end walls to form a bottom closure, interlocking flaps formed on the top edge of one of said end walls and on the adjacent top edge of each of said side walls, said flaps on the side walls terminating short of the other end wall to form a partial top closure, a substantially rectangular flap formed on the top edge of the other end wall, a pair of auxiliary flaps formed on the top edge of each side wall adjacent said other end wall, the edge of each auxiliary flap adjacent the said other end wall forming with said rectangular flap a pouring spout, said rectangular flap being of sufficient length to engage under a portion of said interlocking flaps for retaining said rectangular flap in closed position, said carton being provided with slits extending downwardly a short distance from the top edge between said other end wall and said side walls whereby said rectangular flap may be moved in a direction in the plane of the top to disengage from said interlocking flaps.
